UNITED STATES PATENT OFFICE.

HENRY A. FRENCH, OF DIMONDALE, MICHIGAN.

PUMP.

SPECIFICATION forming part of Letters Patent No. 362,947, dated May 17, 1887.

Application filed February 15, 1886. Serial No. 192,053. (No model.)

To all whom it may concern:

Be it known that I, HENRY A. FRENCH, a citizen of the United States, residing at Dimondale, in the county of Eaton and State of Michigan, have invented a new and useful Improvement 5 in Pumps, of which the following is a specification, reference being had to the accompanying drawings.

My invention relates to pumps, and especially to that class which employs compressed air as a medium to assist and maintain a steady continuous stream of water from the spout or outlet.

The present invention primarily consists in 15 locating the air-pipe and discharge-pipe separate from each other and securing them together at their lower ends by a single connection, which also forms the coupling between the upper and lower cylinders, this connection or coupling thereby serving, first, as a common outlet for both cylinders; second, the outlet for the compressed air from the air-pipe, and, third, the inlet for the water discharged through the water-pipe, whereby I 25 obtain a more direct reaction of compressed air, and the construction of the pump is considerably simplified, made more compact, and the cost of manufacture reduced to a minimum.

30 The invention consists, further, in certain details of construction and combination of parts, as will be hereinafter set forth and claimed.

In the accompanying drawings, Figure 1 is 35 a perspective view of my improved pump. Fig. 2 is a vertical longitudinal section of the same. Fig. 3 is a horizontal section on the line $x-x$ of Fig. 2. Fig. 4 is a side elevation representing a construction of the cylinders 40 when the pump is used for deep wells. Fig. 5 is a detail view of the coupling which serves as the connection between the air and discharge pipes and the two cylinders.

Like letters are used to indicate corresponding parts in the several figures.

Referring to the drawings, A designates the lower cylinder, which is of larger diameter than the upper cylinder, B, said cylinders being made of brass of such dimensions to suit 50 the requirements.

C designates the coupling-piece or connection for the two cylinders, which connection is

substantially trefoil in form, having three cusps or branches, $a a' a''$, connected together and made in a single casting. Each of the 55 cusps or branches of the trefoil connection forms an independent tube, these several tubes being arranged around a common center and molded or cast together. At the central portion of the trefoil casting or coupling, 60 where the three tubes $a a' a''$ join with each other, each of the tubes is left open, as shown clearly in Fig. 3, so as to provide a continuous communication throughout.

The tube, cusp, or branch a of the coupling 65 connection or casting C is screw-threaded inferiorly at its upper and lower ends, $b b'$, to receive the exteriorly-threaded ends of the cylinders B A. It will be observed that the upper end of the lower cylinder, A, screws into 70 the threaded portion b' of the tube or branch a , and the lower end of the upper cylinder, B, works into the threaded portion b of said tube, and in this manner a single connection is provided, which connection will allow the 75 constructing of the cylinder of brass, this being much cheaper than iron or porcelain and having a decidedly higher finish than either material. The top of the upper cylinder, B, is left open for the working of the upper piston or bucket, while the bottom of the lower cylinder, A, has a screw-cap connection with the suction-pipe D, which extends down into the well for any desired depth. The two remaining cusp tubes or branches, $a' a''$, of the 80 trefoil casting, coupling, or connection C are closed at their lower ends or bottoms, but are open at their upper ends, which open upper ends are threaded, as at $c' c''$.

The water-discharge pipe E is threaded at 90 its lower end, and screws into the threaded upper end, c' , of the tube or branch a' , and is arranged in a vertical position, with the usual crook or goose-neck F, forming the discharge-spout, secured or detachably fitted to the upper end of the pipe E. In practice the water-discharge pipe and the crook or goose-neck F are made of separate pieces, having a threaded connection, the former being nickel-plated and the latter painted, so as to present an ornamental appearance.

The compressed-air pipe G is preferably made in two sections or branches, H I, the bottom section, H, being painted and threaded

at its lower end to screw into the threaded upper end, C², of the tube or branch a². The upper end of section or branch H is coupled to the upper section or branch, I, the latter being nickel-plated for ornamentation. The upper end of section or branch I is threaded to screw into the lower end of the air-chamber or reservoir J, which is closed at its upper end and has a solid casting or arm, K, projecting upward therefrom. The upper end of the casting or arm is bifurcated or slotted to provide bearings for the operating handle or lever L. Said handle L comprises the wooden portion d, which forms the handle proper, and the metallic nickel-plated portion e, the wooden portion being fitted in a socket of the metallic portion and bolted thereto. A perforated lug, f, projects from the metallic portion e, which lug fits within the bifurcation or slot of casting or arm K and registers with the perforations therein, a pin or bolt passing through the arm K into the lug f, so as to pivot the handle thereto. The outer or upper end of the metallic portion e of the handle L is bifurcated, as at g, to clasp the upper end of the plunger or piston-rod M, to which it is pivoted, as shown.

The lower end of the plunger-rod M is threaded to receive the upper piston or bucket, N, which comprises the top portion, i, the clamping bottom portion, h, and the packing-ring j, the latter having its upper edge clamped by the bottom portion, h, against the top portion, i. The bottom clamping portion, h, is provided with an angular projection, k, having a screw-threaded opening to receive the threaded upper end of the connecting-rod O, the latter having its lower end connecting with the lower piston or bucket, P. It will be understood that the upper bucket, N, works in the upper cylinder, B, while the lower bucket, P, traverses the length of the lower cylinder, A, both buckets or pistons alternately descending and ascending their respective cylinders at the same time.

Q designates a yoke made in two sections, l m, each of which has two curved or semicircular portions having an intermediate or central straight portion. The curved portion of each section embraces the air and discharge pipes—one section, l, on one side and the other section, m, on the opposite side—so as to form a complete connecting-yoke to hold the two pipes together, the intermediate straight portion of each section l m fitting between the pipes and joined securely together by a bolt and nut, as shown. This yoke Q connects the air and discharge pipes, preferably at the junction of the latter with the crook or goose-neck F.

R designates the flange for supporting the pump, comprising the hollow hub to embrace the air pipe, having a series of projections, n, separated by intervening spaces, o, a binding-screw, p, working through the hub from one side to engage the air-pipe, and thus set the flange in its proper position. Each of the pro-

jections n is perforated to receive bolts, nails, screws, or equivalent means, to allow the fastening of the flange R to the platform of the well. It will be observed that the plunger-rod fits within and works in one of the spaces o separating the projections n, while the discharge-pipe passes through another of the spaces. This flange R, together with the yoke Q, will serve to maintain the relative positions of the air and discharge pipes and keep them firm and stiff and prevent them from separating. This connection also enables the pump to be readily put together and taken apart, leaving only the central opening in the hub to fit to the pipe in case of an imperfect casting. It will also be seen that the plunger-rod can be withdrawn and replaced without having to pull it through the flange, since it is inserted laterally into one of the spaces o.

The yoke Q serves to stiffen that part of the pump above the platform, and enables me to dispense with the usual brace heretofore employed.

When constructing a pump for shallow wells, the upper and lower cylinders should be connected directly together, as shown in Figs. 1 and 2; but for deep wells the two cylinders should be separated, as seen in Fig. 4, 95 a tube, S, serving as the connection between the cylinders. The tube S may be made of any suitable length to suit the depth of the well, while the connecting-rod O for the upper and lower buckets should be lengthened correspondingly, as shown in Fig. 4.

The air chamber or reservoir J is shaped and ornamented to present an attractive appearance.

The operation of my invention is obvious. By the operation of the handle L the plunger-rod carrying the buckets is reciprocated vertically, the upper or force bucket working in the cylinder B and the lower or suction bucket in the cylinder A. Thus while the lower bucket is drawing water into the bottom of the cylinder A from the suction-pipe at the same time it is forcing one half of the water which is in the cylinder A into the upper cylinder and the other half out through the discharge-pipe E. On the return-stroke the upper bucket forces the water which has accumulated in the upper cylinder out through the discharge-pipe, while the water in the bottom of the lower cylinder escapes through the valve in the lower bucket and occupies the space within the lower cylinder above the said lower bucket.

It will be observed that the casting or coupling connection provides but a single outlet for the water in the two cylinders. Since both the air and discharge pipes communicate with this common outlet, the water, when escaping from the cylinders, must necessarily be acted upon by the compressed air within the air-pipe and assure an even and continuous flow of water.

I am aware that compressed-air pipes in double-acting force-pumps is not new, and hence

I lay no broad claim to this construction; but prior devices have either combined the discharge-pipe within the air-pipe or provided independent connections for the air and discharge pipes to the cylinders. The object of the former construction was to prevent water from freezing in the discharge-pipes, as the air-pipe would serve as a protecting cover or cushion for the latter; but when this course is pursued the air-pipe must be constructed very large to receive the discharge-pipe, and, furthermore, the equilibrium of the pump is not maintained. Again, additional joints and couplings are necessitated by this construction, making the pump both expensive and impracticable.

When the air and discharge pipes are located side by side, as in the present invention, but have independent connections with the cylinders, the result is that the compressed air has very little action on the water discharged from the cylinders, since the air-pipe and discharge-pipe are away from each other, and the water escapes up the latter before it can be acted upon by the air. Again, the number of connections or couplings is increased. My invention combines the advantages which both these forms have and overcomes their respective disadvantages. In my construction the air and discharge pipes, being located side by side, serve to maintain the equilibrium of the pump and distribute the strain produced from the operation of the handle. Furthermore, as said pipes have a common connection with the cylinder, the number of parts are reduced, and the air within the air-pipe is necessarily caused to act upon the water discharged from the cylinders, inasmuch as the water must pass into and through the outlet-opening of the air-pipe, which also serves as the inlet for the discharge water-pipe, before it can escape through the latter. I therefore lay stress on the particular arrangement of the air and discharge pipes side and side and independent of each other, said pipes having a common outlet-connection with the cylinders.

The casting, coupling, or connection C can be readily cast, and serves the purpose of a complete and sole connection for the two cylinders and the air and discharge pipes.

To prevent water from freezing in the water-discharge pipe, I provide an opening, T, in the base of said pipe, which is below the effect of frost, and which will allow any water that may be within said pipe to escape through the said opening.

The general construction of my pump is such that the handle may be of the proper distance from the platform to pump with natural ease, while the spout or goose-neck comes within convenient distance, so as not to be too high to lift a pail of water from the spout.

The air and discharge pipes are maintained inseparable from each other, and, being located side by side, maintain the proper balance for the pump.

By reason of the fact that the outlet for the

air-pipe forms also the inlet for the water-pipe, the air is caused to act at all times upon the water, producing a more perfect stream, which is a very valuable feature in a force-pump.

Having thus described my invention, I claim—

1. The combination, with the upper and lower cylinders, of the hollow casting or coupling-piece C, formed in a single piece independent of the cylinders, with three branches or pipes having a continuous unobstructed communication, the main branch forming the connection between the cylinders, and the air and discharge pipes connected, respectively, with the other two branches, as set forth. 75

2. The casting or coupling-connection C, forming three hollow tubes having a continuous unobstructed communication, which tubes are arranged on the same horizontal plane, as set forth. 85

3. The combination, with the upper and lower cylinders, the hollow casting or coupling C, formed in a single piece and comprising three tubes or branches, the main tube connecting at its top and bottom, respectively, with the upper and lower cylinders, and the air and discharge pipes connecting with the upper ends of the two remaining branches, the several branches of the casting having an unobstructed communication, as set forth. 90

4. The casting or coupling piece C, made in a single piece with three branches or tubes having a continuous unobstructed communication with each other, two of the branches being closed at their lower ends only, while the remaining branch is left open at both ends, as set forth. 100

5. The combination, with the upper and lower cylinders, of the hollow casting C, made independent of the cylinders and provided with the tubes or branches, two of the branches being closed at their lower ends, the air and discharge pipes of the pumps connecting, respectively, with the tops of such branches, and the other branch being open at both ends, the upper and lower cylinders connecting, respectively, with such ends, as set forth. 110

6. The casting or coupling piece C, made of a single piece with three branches or tubes, the central or main branch being open at both ends, which are screw-threaded, and the other two branches being open only at the top and screw-threaded at such ends, as set forth. 120

7. The combination, with the upper and lower cylinders, of the hollow casting C, connecting the cylinders and comprising three tubes or branches, the main branch connecting, respectively, at its top and bottom with the upper and lower cylinders, and the air and discharge pipes arranged parallel with each other side by side, and having their lower ends connecting, respectively, with the two remaining branches of the casting, as set forth. 125

8. The combination, with the upper and lower cylinders, of the casting C, comprising three hollow branches or tubes, one of which serves

as the connection for the cylinders, the air and discharge pipes arranged side by side and connecting with two other branches, all three branches having a continuous unobstructed communication, and the air-pipe extending up, so as to provide a support for the handle, as set forth.

9. The upper and lower cylinders, threaded at their lower and upper ends, in combination with the coupling-piece, threaded at its upper and lower ends to receive the said threaded

ends of the cylinders, whereby the cylinders may be constructed of different metal from the coupling-piece and replaced at will, as set forth.

In testimony that I claim the foregoing as my own I have hereto affixed my signature in presence of two witnesses.

HENRY A. FRENCH.
